PORTABLE STEREO PHONOGRAPH

George M. Buckler, Baldwinsville, N.Y., assignor to General Electric Company, a corporation of New York

Filed Jan. 7, 1966, Ser. No. 525

Term of patent 14 years

(Cl. D56—4)

F7 — 1.

F7 — 2.

F7 — 3.

FIG. 1 is a disassembled perspective view of a stereo portable phonograph, showing my new design;

FIG. 2 is a perspective view of the phonograph in assembled position;

FIG. 3 is a top view of the phonograph in assembled position;

FIG. 4 is an elevation view of the phonograph in assembled position;

FIG. 5 is an end elevation view of the phonograph in assembled position, the opposite end being substantially a mirror image thereof; and

FIG. 6 is a bottom view of the phonograph in assembled position.

The dominant features of my new design are shown

in solid lines in the drawings. The loudspeaker grilles being fragmentarily shown are continuous within the boundaries indicated.

I claim:

The ornamental design for a portable stereo phonograph, substantially as shown and described.
